[57] CLAIM

The ornamental design for a housing for a vending machine, as shown and described.

DESCRIPTION

FIG. 1 is a front and right side perspective view of a housing for a vending machine showing my new design;

FIG. 2 is a left side elevational view thereof;

FIG. 3 is a right side elevational view thereof;

FIG. 4 is a top plan view thereof;

FIG. 5 is a bottom plan view thereof; and

FIG. 6 is a rear elevational view thereof;

The broken line showings are environmental only and form no part of the claimed design.
